UNITED STATES PATENT OFFICE

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK

SASH AND FRAME CONSTRUCTION

Application filed December 12, 1927. Serial No. 239,584.

This invention relates to improvements in sash and frame constructions and more particularly to a construction which eliminates the necessity of using latches for securing the sash in adjusted position and to a construction involving other advantageous features and refinements.

While the construction about to be disclosed is adaptable for use in various different ways it finds particular utility in connection with buses and the like. In motor vehicles such as buses difficulty is experienced in fitting the sashes to the frames because of the variances in the distance between the frame members. If a standard or uniform size sash is employed as is the custom it is found that in some instances the sash fits the frame member too tightly and in other instances too loosely so that on the whole the fitting of sashes to the frames is difficult, expensive and otherwise unsatisfactory. Furthermore because of the weaving of the frame of the vehicle in use and by reason of other distortion of the sash frames, difficulty is frequently experienced in raising and lowering the sash. Many of the heretofore known forms of sash have also been found to be objectionable because the construction necessitated the use of latches or the like to hold the sash in adjusted position.

It is therefore one of the primary objects of this invention to provide a latchless sash and frame construction which may be readily assembled irrespective of variations in the distance between the frame members or the dimensions of the sash and which may be readily raised and lowered without liability of the same binding. In accomplishing this I provide a frame, the side members of which have their inner walls or portions thereof transversely oppositely inclined thus providing a tapering opening for receiving the sash. Resilient means is associated with the sash normally urging the sash transversely of the frame members toward the converging edges of the inclined walls. Notched members are associated with the frame members adjacent the converging edges of the inclined walls, the sash being urged into engagement with these notched members by the resilient means

heretofore referred to. As a consequent in raising or lowering the sash the same is moved transversely of the frame members against the action of this resilient means thus positioning the sash in that portion of the space between the frame members which is wider. This permits the sash to be freely raised or lowered and when released the resilient means again urges the sash transversely toward the converging edges of the inclined side walls and into intimate engagement with these side walls and also into engagement with the notched members. By reason of the tapering character of the frame opening sashes of varying width may be accurately fitted within the frame and variance in the distance between the frame members is also of no consequence.

The several objects, advantages and novel details of construction of this invention will be made more apparent as this description proceeds, especially when considered in connection with the accompanying drawings wherein:

Figure 1 is an elevational view of a sash and frame constructed in accordance with this invention.

Figure 2 is a vertical sectional view taken substantially on the plane indicated by line 2-2 in Figure 1.

Figure 3 is an enlarged detail sectional view taken substantially on the plane indicated by line 3-3 in Figure 1.

Figure 4 is a similar sectional view taken substantially on the plane indicated by line 4-4 in Figure 1, and

Figure 5 is a detail sectional view showing an application of the invention to a metal bus construction.

Referring now to the drawings and more especially to Figures 1 to 4 inclusive it will be noted that there is illustrated a frame which consists essentially of a pair of spaced side members 10, a sill 11 and a header 12. A sash is slidably mounted in the frame and consists of a top member 13 a bottom member 14 and a pair of side members 15. The members 13, 14 and 15 of which the sash is composed may be of any desired form or construction but are formed with channels or means

providing a channel by means of which the glass 16 is secured in place. The lower sash member 14 is formed with a channel or recess 17 in which a tubular compressible weatherstrip 18 is secured which in the closed position of the sash is adapted to engage the sill 11 to weatherproof the sash at the lower edge thereof.

The upper sash member 13 is formed with return-bent portions or tongues 19 engaging in grooves or recesses in a weatherstrip 20 which weatherstrip is formed with a laterally projecting lip or extension 21 adapted for engagement with a surface or wall 22 formed interiorly of the header 12. This surface 22 is inclined with respect to the path of travel of the sash and as the sash approaches its closed position lip 21 engages surface 22 and thus weatherproofs the sash at the upper edge thereof.

In the construction shown in Figures 1 to 4 the pillars or side frame members 10 are illustrated as of wooden construction, and in such cases it has been found to be desirable to associate or secure to the inner face of each pillar 10 a plate or face member 23 which in effect becomes a part of the side frame members. This plate member is bent to provide a transversely inclined portion 24 and a laterally extending flange portion 25 constituting a portion of the sash guide. The other edge of each plate member is bent to provide a member 26 which is notched longitudinally thereof as indicated at 27. While the notched member 26 is here shown as formed integrally with plate member 23 and while this is a convenient form of construction nevertheless these notched members may be constructed separately and secured to the side frame members in any desired manner.

The side sash members 15 are each formed with a portion or surface 28 adapted for engagement with the inclined walls 24 of the pillars or frame members. As shown this portion of the sash members is curved or arcuate in cross section and from an examination of Figure 4 it will be noted that the sash members 15 are recessed to accommodate and receive weatherstrips 29.

Means is provided for resiliently urging the sash transversely of the frame into engagement with the inclined walls of the latter and toward the converging edges thereof or in other words toward the narrower portion of the frame. While any desired form of resilient means may be employed there is illustrated herein coil springs 30 located within the side sash members 15 which act upon plungers 31 slidably mounted in the sash members. These plungers 31 engage the flange member 25 and thus urge the sash member transversely of the frame and into engagement with the inclined walls thereof. The side sash members may each be formed with a laterally extending lip or

flange 32 which acts as a cover flange and cooperates with the flanges 25 carried by the frame members to conceal the plungers 31 and to protect the same.

The lower sash member is provided with a tongue or projection 33 which may be formed separately and secured thereto or may as illustrated herein be formed of an integral part of the lower sash member 14. This tongue or lip 33 is adapted for engagement with the notched members 26 for securing the sash in any of its adjusted positions.

It will be obvious that the sash may be easily raised and lowered by gripping handle members 34 and moving the sash transversely against the action of the spring pressed plungers 31 toward the diverging edges of the inclined side walls of the frame or in other words between those portions of the side frame which are spaced wider apart. This will give ample clearance between the sash and frame to permit the sash to be readily raised or lowered and if the sash has been raised when the same is released the spring pressed members will urge the same transversely of the frame and cause the lip 33 to engage in the adjacent pair of notches 27. When the sash is in its lowermost or closed position the lip 33 extends into the recess formed by cutting away the lower edge of the notched members as indicated at 35.

In Figure 5 there is illustrated an adaptation of this invention to all metal construction wherein a pillar constituting one of the frame members is indicated by the reference character 36 and as shown consists of a member substantially T-shaped in cross section. Brackets or anchor members 37 are secured to each pillar 36 at spaced intervals throughout its length and a member indicated generally by the reference character 38 is shown as entirely enclosing the pillar 36 and anchor 37. This member may be conveniently formed of sheet metal substantially in inverted U-shape in cross section. The base of the U is formed with shouldered portions 39 adapted for snap engagement with the head of the T-shaped pillar member. The member 38 is formed with laterally extending flanges 40 constituting a portion of the sash guide and retainer plates 41 are secured to the anchor members 37, the ends 42 of these members constituting flanges completing the guides for receiving the sash. That portion of the member 38 adjacent each flange 40 is shaped to provide an inclined wall 43 for cooperation with the sash as in the previously described form of construction.

With a sash and frame constructed in accordance with the present invention it will be obvious that sashes may be more readily fitted to the frames without regard to variances in the distance between frame members or in width of the sash. The tapering side walls of the frame and the spring pressed

means for urging the sash into engagement therewith will under ordinary conditions provide sufficient latitude to permit of a satisfactory fit between the sash and frame despite any ordinary variances in dimensions. Furthermore by reason of the fact that the sash may be moved laterally toward the diverging edges of the inclined side walls of the frame a sufficient clearance between the sash and frame is always possible to thus enable the sash to be readily raised and lowered. The spring pressed means normally urging the sash into engagement with the walls of the frame will compensate for wear between the parts and prevent rattling. Furthermore with the herein described construction the sash may be held in its adjusted position without necessitating the use of a complicated latch mechanism.

Obvious changes in the details of construction and rearrangement of parts may suggest themselves to those skilled in this art and to this end reservation is made to make such changes as may come within the purview of the accompanying claims.

What I claim as my invention is:—

1. In a sash construction, a frame including spaced transversely oppositely inclined walls, a sash and a spring pressed member carried by said sash for normally urging said sash transversely of the frame maintaining the same in engagement with said inclined walls.

2. In a sash construction, a pair of spaced pillars the adjacent walls of which are transversely inclined in converging relation, a sash located between said pillars in engagement with said walls and a spring pressed member on said sash normally urging said sash transversely of said frame toward the converging edges of said walls.

3. In a sash construction, a pair of spaced frame members, a vertically extending latch bar associated with one of said frame members and provided with a plurality of latch recesses, a sash capable of movement transversely of said frame members and engageable with said latch bar and a spring actuated element acting on said sash to normally urge the same toward said latch bar, for the purpose set forth.

4. In a sash construction, a pair of spaced frame members, a sash located therebetween and movable longitudinally thereof, said sash being also capable of movement transversely of said frame members, a vertically extending notched member and means on said sash engageable with said notched member by reason of said transverse movement.

5. In a sash construction, a pair of spaced frame members provided with oppositely transversely inclined wall portions, a sash located between said frame members and movable longitudinally thereof and resilient means on said sash normally urging said sash

transversely of said frame members toward the converging edges of said inclined wall portions.

6. In a sash construction, the combination with a pair of spaced frame members, of a sash located therebetween and movable longitudinally thereof, means for mounting said sash for limited movement transversely of said frame members, a notched member and resilient means normally urging said sash transversely into engagement with said notched member.

7. In a sash construction, a pair of spaced frame members, sash guiding means on said frame members, the walls of said frame members being transversely oppositely inclined, a sash movable longitudinally of said frame members guided by said guiding means and resilient means arranged between said sash and guiding means for urging said sash transversely of said frame members in the direction of the converging edges of said inclined walls and into engagement with said walls.

8. In a sash and frame construction, a frame including a header, a slidably mounted sash having an edge extending within said header, a weatherstrip secured to said edge and provided with a laterally projecting lip, and a surface on said header inclined with respect to the general direction of travel of said sash engageable by said weatherstrip lip in the closed position of said sash.

9. In a frame and sash construction, a frame member including a pillar T-shaped in cross section, a member enclosing said pillar and having a snap engagement with the head of said T, said member being formed with a flange and an inclined wall portion, a retainer plate secured to said pillar and cooperating with said flange to form a sash guide and a sash slidably mounted in said guide.

10. In a sash construction, in combination, a pair of spaced frame members provided with transversely oppositely inclined walls, a sash located therebetween and movable longitudinally thereof, means for mounting said sash for limited movement transversely of said frame members, a notched member secured to one of said frame members adjacent the converging edge thereof and resilient means normally urging said sash transversely of said frame members into engagement with said inclined walls and said notched member.

In testimony whereof I affix my signature.

WILLIAM S. PRITCHARD.
